UNITED STATES PATENT OFFICE.

JACOB S. KATZIN, OF NEWARK, NEW JERSEY, ASSIGNOR OF ONE-FOURTH TO JACOB S. KATZIN, ONE-FOURTH TO HARRY COLTON, ONE-FOURTH TO LEO SAMEL, AND ONE-FOURTH TO MORRIS SCHARFF, ALL OF NEWARK, NEW JERSEY.

FLUSH-TANK SIPHON.

1,192,785.

Specification of Letters Patent. Patented July 25, 1916.

Application filed May 6, 1916. Serial No. 95,850.

To all whom it may concern:

Be it known that I, JACOB S. KATZIN, a citizen of the United States, and a resident of Newark, in the county of Essex and State of New Jersey, have invented a new and Improved Flush-Tank Siphon, of which the following is a full, clear, and exact description.

This invention relates to valves and closets, and has particular reference to flush tank apparatus.

Among the objects of the invention is to provide a flushing device for toilet tanks or the like adapted to be readily fitted to either high or low down tanks, and applicable also to tanks now in use without the necessity for disconnecting the tank from the outlet pipe.

Another object of the invention is to improve the construction of the siphon constituting the means for flushing the tank, said siphon being preferably of tubular construction, having its down leg fitted into the spud constituting the connection between the outlet pipe and the tank, and also including a dome-shaped up leg adjustably connected to the top of the down leg so as to vary the rapidity of outflow of the water, depending upon the adjustment of the siphon for high tanks or low tanks, said siphon being made preferably also of a material adapting it especially to the adjustable adaptation.

Another object of the invention is to provide an improved means for regulating the admission of water into the top of the siphon to variably break the siphonic action at any time prior to the fall of the water to the bottom of the up leg.

Another object of the invention is to improve the means for initiating the siphonic action by plunging the float ball downwardly into the water.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like

reference characters designate the same parts in the several views, and in which—

Figure 1 is a vertical longitudinal section through the center of the siphon; Fig. 2 is a plan view; Fig. 3 is a detail of a special connection adapting my improvement to existing tanks and outlets; Fig. 4 is a large detail view of the needle valve mechanism; and Fig. 5 is a detail of the siphon adjustment.

Referring now more particularly to the drawings, I show at 10 a flush tank indicated as of the low down type, for which my improvement is particularly well adapted.

11 indicates the outer pipe, and 12 is the coupling or spud making the permanent and water-tight connection between the bottom of the tank and the pipe 11. The means for connecting the spud and the outlet pipe to the tank may be of any well known or conventional character, and in fact may be the same as are in common use, my improvement being designed to be connected directly to existing installations.

The tank is provided with an inlet valve 13 or ball cock, shown at 13, of any suitable construction or location, but being indicated as including a lever 14 pivoted at 15. An arm 16 is connected to the lever 14 by means of an adjustable joint 17 to provide adjustment of the float 18, without the necessity for bending of the arm. The arm shown in Fig. 2 is in the nature of a yoke bail adapting it to operate on opposite sides of the siphon S. The free ends of the two parts of the arm 16 are turned inwardly to provide cone bearings 19 in axial horizontal alignment with each other and projecting into correspondingly shaped sockets in the end disks 20 of the float, the float being preferably in the form of a true cylinder with its axis horizontal and transverse with respect to the tank. A stay rod 21 connects the two parts of the arm 16 so as to stiffen the structure and prevent spreading of the bearing portions. This construction provides a most suitable support for the float, preventing twisting or tilting around a longitudinal horizontal axis, such as is found to be incident to other structures of this general type wherein the arm is single and extends around the flushing mechanism.

As above premised, the flushing mechanism comprises a siphon of tubular form, or one which comprises a down leg 22 of straight tubular form having both ends 5 open, and an up leg 23 in the nature of a cylindrical tube having its upper end closed in the nature of a dome, and spaced upwardly from and surrounding the upper end of the down leg 22. For reasons which will 10 appear presently, I construct the siphon legs 22 and 23 of some suitable transparent material, such as glass. The construction of the siphon of glass adapts it for several important functions, among which may be 15 noted the adaptability for easy and satisfactory adjustment of the means for controlling the inlet of water, having reference particularly to the means employed herein for initiating the siphonic action, that is to 20 say, the normal water level should be in a plane at or slightly below the upper edge of the down leg 22. With the siphon constructed of transparent material, it is possible to always regulate the inlet mechanism 25 with accuracy and convenience, even though the siphon is installed and set for operation. To initiate the siphonic action, the float 18 is plunged by suitable means into the water, the displacement of which causes a corresponding rise in the level of the water over- 30 flowing into the down leg 22 from all sides, and hence the importance of having the normal water level at or close to the plane of the top of the down leg. This form of 35 siphon is adapted especially for low down tanks where a large volume of outflow is necessary to cause the operation of the siphon. As soon as the overflow of the water into the member 22 takes place from 40 all sides, and the water flows down in the form of a cylinder, the air communication is shut off immediately and the siphonic action takes place promptly, causing the water to flow from the tank upwardly 45 through the open lower end of the member 23 until the siphon is broken at the desired time, either when the water level reaches the lower end of the up leg or at some prior time if sufficient air is introduced into 50 the dome. Furthermore, the construction of the siphon of glass is most expeditious and cheap, adapting it for general use at a reasonable price, and being of a sanitary material, will not only be always kept clean, 55 but the condition may always be inspected and determined, and the volume of water flowing may always be seen and regulated.

The top or dome 23' of the up leg is somewhat rounded to facilitate the construction of the same and also the outflow of water therethrough into the down leg. The dome is connected to the down leg adjustably as by means of a pair of threaded standards 24 connected at their lower ends

in any suitable manner to the upper end of 65 the down leg 22 and extending through holes 25 in the dome. Pairs of lock nuts 26 are employed upon the threaded upper ends of the standards 24 to determine the elevation of the dome with respect to the member 70 22, and thereby will be determined the outflow area between the lower end of the leg 23 and the bottom of the tank. When applied to high tanks, the outflow area may be 75 smaller than for low tanks where the maximum rapidity of flow is required.

Since the normal water level in the tank is determined at or about the level of the upper end of the down leg for the most satisfactory operation of the siphonic action 80 initiating devices employed by me, and it is at many times desirable to break the siphon before all the water is withdrawn from the tank, I provide regulatable means to admit air into the dome. In other words, the best 85 plumbing practice demands that the amount of water discharged from the tank shall be enough for the purpose and no more. An excessive outflow of water will not only be a waste of water, but is apt to cause a second 90 siphoning of the bowl. I form a hole 27 in the top of the dome, and lock therein a nipple 28, by means of lock nuts 29, the nipple being externally threaded from one end to the other for the accommodation of said 95 lock nuts, and also for a cap 30. The nipple has an open lower end and its upper end is closed with a cone 31 having several air holes 32 therethrough. The cone has an outwardly projecting point or needle 31' coöperating with the central hole 30' in the cap. The cap is movable down upon the nipple so as to bring the needle point more or less into the hole 30', thereby obstructing the air passage accordingly. This type of needle valve 100 105 to control the admission of air into the dome is very delicate as to adjustment, but exceedingly reliable after being once adjusted. By the provision of air inlet means described herein, air in small quantities is drawn into 110 the dome during the operation of the siphon, the amount of the air thus admitted determining the time of breakage of the flow of the siphon as may be desired prior to the fall of the level of the water to the lower end 115 of the up leg. In other words, by opening the air inlet by the unscrewing of the cap 30, the siphonic action may be stopped soon after it is initiated and thereby the amount of water discharged is comparatively small, 120 125 and the action is practically noiseless.

I will now describe the means for actuating the float to initiate the siphonic action, the means being shown as applicable especially to low down tanks, but with slight modification the mechanism will be adapted to high tanks.

A handle 33 is connected on the outer end

of a rock shaft 34 journaled freely in the tank adjacent one end thereof. This handle 33 is adapted to be swung laterally through approximately 90 degrees or less, as may be required to start the siphon. The extent of movement of the handle may be limited by a finger 35 connected by a collar and set screw 36 to the rock shaft just within one side wall, the finger being adapted to abut 10 against the end wall of the tank.

37 indicates an arm or lever having two projecting ends of any suitable length or form and coöoperating with the upper surface of the roller float 18. The arm 37 is 15 adjustably connected to the rock shaft by means of a hub 38 and set screw 39, whereby the arm may be properly positioned in accordance with the upward adjustment of the float to admit water up to the level of the leg 22. When the handle 33 is turned so as to cause the arm 37 to force the float downwardly, the water displaced by the float will 20 cause the overflow into the upper end of the leg 22, and the starting of the siphon, as 25 already explained. The water or as much of it as required, will then be siphoned from the tank, the float going down with the water and opening the inlet valve 13. It is to be noted especially in this connection that the 30 action of the operator in depressing the float, causes immediately an opening of the inlet valve with the corresponding inflow of water, and thereby the overflow or siphon starting effect is increased or accelerated. 35 In the usual types of flushing devices, the ball cock is not opened until after the level of the water falls, whereas in this case, the opening of the valve takes place before the water begins to fall. The arrangement of 40 the float and rock shaft depressing means therefor is such that the handle cannot be turned far enough to cause the arm 37 to pass the dead center of the roller float, hence it is impossible for the tripping mechanism 45 to become locked even though the handle be held for a great length of time. It is to be noted that the float constructed and mounted as explained, upon the yoke-shaped arm 16 constitutes in effect an anti-friction bearing 50 for the arm 37. It follows, therefore, that the power required to initiate the siphonic action is no more, and is practically less, than in the ordinary low down tank devices.

In the construction of the down leg 22 of 55 glass, it is preferable to cast or otherwise form thereon a large thread 22', and hence to adapt the same to present installations, I may employ a coupling 38, as indicated in Fig. 3, made of metal or the like, one end 60 having a small thread to connect with that type of spud having an internal thread and having at its other end a large thread to correspond with the large thread of the member 22.

I claim:

1. The combination with a low down float tank having permanent spud connection with the outlet and a vertically adjustable float to control the admission of water into the tank, of a siphon comprising a fixed 7 ; valveless down leg secured into said spud and having at its upper end a plurality of vertically extending parallel threaded standards, said siphon also including a straight tubular up leg having a plurality of holes 75 in its otherwise closed upper end through which said standards project, pairs of nuts to lock the up leg at a predetermined elevation above the bottom of the tank according to the desired outflow capacity, said up leg 80 being formed of transparent material so that the water level with respect to the top of the down leg may be determined directly by inspection, and pivoted means acting downwardly upon the float to displace the water 85 in the tank and open the inlet valve to cause the overflow of water into the down leg and start the siphonic action.

2. The combination with a flush tank and a valveless siphon to discharge the water 90 therefrom, of a ball cock mechanism to refill the tank, said ball cock mechanism including a lever having a yoke-shaped arm adjustably connected thereto and a cylindrical float journaled in the free end of the yoke-shaped 95 arm on a horizontal transverse axis, said yoke-shaped arm extending along both sides of the siphon, and lever mechanism acting with rolling friction upon the float to cause the depression of the same to initiate the si- 100 phonic action.

3. In a flush tank of the character set forth, the combination of a valveless siphon, an inlet valve, a lever connected to the inlet valve and including an arm extending along 105 the siphon, a float pivoted for free rotation in the free end of the arm on a horizontal axis, a rock shaft journaled in the tank parallel to said axis, a handle to rotate the rock 110 shaft, and an arm connected to the rock shaft and bearing upon the float whereby when the rock shaft is rotated the float will be depressed to displace a certain amount of water and open the inlet valve to start the si- 115 phonic action.

4. In a flush tank mechanism, the combination with a tank and fixed outlet connections therewith including a spud; of a siphon including a valveless straight vertical down leg having a coarse thread at its lower end 120 fitted into said spud, a straight tubular up leg of transparent material surrounding the upper end of the down leg, a plurality of standards extending between the two legs whereby the up leg is adjustably supported 125 upon the down leg, the otherwise closed upper end of the up leg being provided with an opening, and a needle valve device fitted in

said opening, said needle valve device comprising a nipple having an exterior thread from one end to the other and terminating in a central needle, and a cap having a hole in alignment with said needle threaded upon the upper end of the nipple; means to control the inlet of water so as to provide a nor-

mal water level close to the plane of the upper end of the down leg, said last mentioned means including a pivoted float; and means acting downwardly upon said float to cause the immediate overflow of the water into the down leg to start the siphonic action. 10

JACOB S. KATZIN.
